(57) CLAIM

The ornamental design for a roller for cosmetic purposes, as shown and described.

DESCRIPTION

FIG. 1 is a front, right side, and top perspective view of a roller for cosmetic purposes according to the novel design;

FIG. 2 is a front view of a roller for cosmetic purposes according to the novel design;

FIG. 3 is a right side of a roller for cosmetic purposes according to the novel design; the left side view is a mirror image of the right side view;

FIG. 4 is a top plan view of a roller for cosmetic purposes according to the novel design;

FIG. 5 is a bottom plan view of a roller for cosmetic purposes according to the novel design; and,

FIG. 6 is a rear view of a roller for cosmetic purposes according to the novel design.

The broken lines included in the drawings depict elements that are not part of the claimed design.
